UNITED STATES PATENT OFFICE.

AMOS GOSPER, OF CAMPERDOWN, NEAR SYDNEY, NEW SOUTH WALES, AUSTRALIA,
ASSIGNOR TO GEORGE HUGH FOSTER, OF MARRICKVILLE, NEAR SYDNEY, NEW
SOUTH WALES, AUSTRALIA.

EXPANSIBLE BORING TOOL.

Application filed January 14, 1925. Serial No. 2,450.

To all whom it may concern:

Be it known that I, AMOS GOSPER, a subject of the King of Great Britain, residing at Camperdown, near Sydney, in the State of New South Wales, Commonwealth of Australia, have invented new and useful Improvements in Expansible Boring Tools (for which I have filed application in Australia, Dec. 11, 1923), of which the following is a specification.

This invention relates to an improved expansible boring tool for forming undercut holes in timber and other material, and it has been devised having for its principal object the provision of a boring tool that will accurately and expeditiously bore holes of uniform width for portion of their length but enlarged at their inner ends, while simultaneously with the formation of the said enlarged portions counter-sinks are formed at the entrance ends of the holes. Holes so formed are used in the jointing of adjacent members in woodwork by the use of trenails which are adapted to be expanded at their end portions, and for various other purposes in joinery.

The invention provides an improved expansible boring tool which is self-contained and furnished with means for stabilizing its operative integers, and means for synchronously returning the cutter and its control member to initial position immediately upon completion of boring.

Reference being had to the accompanying drawings:

Figure 1 is a perspective view of the improved expansible boring tool.

Figure 2 is a vertical sectional view of the boring tool, showing the arrangement of its integers prior to boring.

Figure 3 is a vertical section showing the arrangement of the tool integers when that portion of the hole of uniform width is being bored.

Figure 4 is a vertical section illustrating the integers of the tool when the lower expanded end of the hole is being bored and the entrance end of the hole is being countersunk.

The improved expansible boring tool comprises a cylindrical casing 2 fitted with a screw-cap 3, and having an upper ball bearing 4 and a lower ball bearing 5 for a spindle 6 which latter is a slidable fit in a

guide hole formed centrally in said screw-cap. This spindle is formed having a tang 7 at its upper end to facilitate the attachment of the boring tool to a drilling machine or the like, whereby the spindle 6 can be rotated at high speed.

Formed in the lower end of said spindle 6 is a slotway 8, wherein is accommodated a control tongue 9, that is pivoted at its lower end upon a short pin 10 in said slotway. This control tongue has a straight edge portion 11, which does not project exteriorly of the spindle 6 and it is constructed having an upper end portion 12 that inclines outwardly from said straight edge portion.

A tool-holder 13 is formed on, or may be affixed to, the lower end of the pivoted control tongue 9, and fitted in said tool-holder is a boring tool or cutter 14 having its opposite edges concaved and thickened at its lower end. A bevelled cutting member 15 is formed on the lower end of the said tool holder 13, and it serves to countersink the upper end of the hole being bored by the tool.

Fitted around the spindle 6, beneath the upper ball-bearing 4 is a thrust collar 16 having fibre seating washers 17. A coiled spring 18 encircles the spindle 6 and the upper end of the control tongue 9, and it is seated against the lower ball-bearing 5 and the washers 17 on the thrust collar 16.

In use, the tang 7 is first connected to a drilling machine or the like, and the spindle 6 is rotated at comparatively high speed and moved downwardly through the ball-bearings 4 and 5 in the casing 2 against the tension of the coiled spring 18. The boring tool or cutter 14 is thus brought against the work-piece and it bores a hole of predetermined depth and having uniform width, until such time as the outwardly projecting and inclined portion 12 of the pivoted control tongue 9 is forced inwardly into the slotway 8 by contact with the lower ball bearing 5—see Figure 4. As the upper end of the control tongue 9 is moved inwardly into said slotway 8, the tool holder 13 is moved slightly outwardly and the boring tool or cutter 14 is inclined to the axis of the spindle 6 to progressively form a hole portion of increasing width at the lower end of the hole portion which is of uniform

width. Simultaneously with the outward movement of the cutter 14 to form the enlarged hole portion, the cutting member 15 at the lower end of the tool holder 13 bears against the work-piece and counter-sinks the entrance end of the hole having its major portion of uniform width.

5 The tension exerted upon the coiled spring 18 encircling the spindle 6 during the feed-
10 ing movement of said spindle ensures the synchronous return of the cutter 14 and the pivoted control tongue 9 to initial position immediately following the boring of a hole of the character described.

15 The lower end of the cylindrical casing is, or may be, provided having spikes 19 to grip the work-piece, and said casing may also be formed having milled portions 20 to enable a tight grip to be maintained upon
20 the tool during boring operations.

It will be readily understood by artisans that different cutters 14 can be interchangeably fitted in the tool-holder 13 and that required adjustments can be made in the
25 integers of the improved expandible boring tool whereby holes of different length and having varying degrees of undercut at their lower ends can be rapidly formed.

What I do claim is:—

30 1. An expandible boring tool comprising, a casing, an upper and a lower ball-bearing

in said casing, a spindle longitudinally movable in said ball-bearings, a slotway formed in said spindle, a tongue pivoted at its lower end in said slotway, an outwardly inclined member at the upper end of said tongue and projecting exteriorly of said slotway, a thrust collar fast on said spindle, a coil spring around said spindle seated between said thrust collar and the lower ball-bearing, a tool-holder at the lower end of said tongue and a cutting tool in said tool holder, the inclined projecting member on said tongue being adapted to contact with the lower ball-bearing when a hole of
40 uniform width of required depth has been bored and thus de-align said cutting tool to undercut the hole and complete the boring operation.

2. An expandible boring tool according to
claim 1, wherein the tool-holder is constructed having a bevelled cutting member to form counter-sinks at the entrance ends of the holes being bored simultaneously with the undercutting of said holes at the
45 inner ends.

In testimony whereof I affix my signature in presence of two witnesses.

AMOS GOSPER.
